UNITED STATES PATENT OFFICE.

HARRY RUBINSON, OF DES MOINES, IOWA.

JAR-CLOSURE DEVICE.

1,426,605.

Specification of Letters Patent. Patented Aug. 22, 1922.

Application filed April 3, 1922. Serial No. 549,110.

To all whom it may concern:

Be it known that I, HARRY RUBINSON, a citizen of the United States, and a resident of Des Moines, in the county of Polk and 5 State of Iowa, have invented a certain new and useful Jar-Closure Device, of which the following is a specification.

The object of my invention is to provide a jar closure device of simple, durable and 10 comparatively inexpensive construction.

More particularly, it is my intention to provide a closure member for jars or the like, the closure member being so designed that it may be received and coact with a 15 portion of the jar for securely holding the cover member in position.

Still another object is to provide a cover member for a jar, having a pair of outwardly extending arms formed thereon and 20 notches provided in the jar for receiving the arms for securely holding the cover member in position.

Still another object is to provide a cam surface adjacent to the notches in the jar, 25 whereby a slight rotation of the cover member in either direction will cause the arms of the cover member to engage the cam surfaces for forcing the cover member downwardly against the jar, whereby it may be 30 securely locked in position.

Still another object is to provide the arm members on the cover long enough, so as to project out beyond the side of the jar, so as to form means, whereby it may be 35 engaged for rotating the cover and moving it to either open or closed position.

Still another object is to provide resilient bands formed on the arms of the cover member, so that the cover member may be 40 yieldingly forced into closed position.

With these and other objects in view, my invention consists in the construction, arrangement and combination of the various parts of my device, whereby the objects 45 contemplated are attained, as hereinafter more fully set forth, pointed out in my claims, and illustrated in the accompanying drawings, in which:

Figure 1 is a side elevation of a jar with 50 my improved cover member shown thereon.

Figure 2 is a top view of the jar with the cover member removed.

Figure 3 is a sectional view taken on the

line 3—3 of Figure 2, with the cover member shown in section.

Figure 4 is a top view of the cover member; and

Figure 5 is a slightly modified form of the cover member.

In the accompanying drawings, I have 60 used the reference numeral 10 to indicate an ordinary jar, which is provided with a contracted neck 11 and an enlarged bead or rim 12 projecting upwardly from the neck 11.

The rim 12 is provided with an enlarged 65 opening 13 and a small contracted opening 14, whereby a shoulder or annular rabbet 15 is provided. The passageway 16, which extends through the neck 11 is smaller in diameter than the opening 14. The main 70 body portion of the jar 10 is larger in diameter than the opening 16 in the neck 11. The purpose of the annular rabbet or shoulder 15 will be hereafter more fully set forth.

The rim 12 is provided with a pair of openings 17, which are substantially the shape of an inverted T. The openings 17 are provided with a pair of cam surfaces 18, as clearly illustrated in Figure 1 of the 80 drawings. At the extreme ends of the openings 17 and adjacent to the inner lower ends of the cam surfaces 18 are provided notches 19, the purpose of which will be hereafter more fully set forth.

In order to seal the jar, I provide a cover member 20, having a shoulder 21, which is designed to be received in the rabbet 15. A rubber band or jar ring 22 may be used by placing it within the annular rabbet 15, 90 whereby the cover member 20 will rest thereon. The cover member 20 is provided with a pair of outwardly, oppositely extending arms 23. The arms 23 are provided with a rubber ring 24. The upper portion of the opening 17 is just large enough to permit the arms 23 to be extended therethrough.

When the arms 23 are extended therethrough, a portion thereof will project out beyond the sides of the jar, so that they may 100 be engaged by the fingers of an operator for rotating the cover member in either direction a slight amount. The rubber band 24 will engage one of the cam surfaces 18 of each of the openings 17.

The continued rotation of the cover mem-

ber 20 will cause the arms 23 to be received in one of the notches 19 of each of the openings 17. When the arms 23 are received in the notches 19 of the openings 17, then the jar cover member 20 will be held in locked position.

When it is desired to open the jar, all that is necessary is to rotate the cover member towards the upper extension of the opening 17, and when the arms 23 register with the upper extension of the opening 17, then the entire cover member may be lifted up and away from the jar.

It will be understood that when it is desired to seal the jar, the cover member 20 may be rotated in either direction, and when doing so, the cover member will be caused to engage one of the notches 19 of the openings 17.

20 The jar 10 may be made of heavy glass or of some other suitable material. The cover member 20 may be made of steel stampings or other suitable material.

The providing of the rubber ring 24 gives 25 the cover member 20 a chance to move up and down a slight amount.

The rubber jar ring 22 causes the connection or the sealing ability of the cover member 20 to be greatly increased, so that when 30 the cover member 20 is in locked position, the contents of the jar will be thoroughly sealed.

35 The main body portion of the cover member 20 may be pushed downwardly, so as to permit the easy rotation of the cover member, when moving it to locked position.

In Figure 5 of the drawings, I have shown a slightly modified form of cover member, in which form, 25 refers to the 40 cover member, which is similar in outline to the cover member 20. The cover member 25 is provided with a pair of short arms 26, having rubber bands 27 thereon. The arms 26 are just long enough, so that when 45 they are moved to locked position, their outer edge is flush with the surface of the jar.

In order to engage the cover member for 50 rotating it, I provide a square opening 28, in the main body portion of the cover member 25. Any sort of a tool or crank, having a square end thereon, may be inserted into the opening 28 for rotating the cover member 25.

55 From the construction of the parts just described, it will be seen that I have provided a very efficient cover member for a jar or other container, which may be readily and easily opened and closed.

60 Another advantage of my device is that the cover member when once made does not

need to be replaced, as is true with the ordinary cover members, now used upon Mason fruit jars for canning.

Some changes may be made in the arrangement and construction of the various parts of my device, without departing from the essential features and purposes of my invention, and it is my intention to cover by my claims, any modified forms of structure or use of mechanical equivalents, which may be reasonably included within their scope.

I claim as my invention:

1. In combination with a jar having a 75 pair of oppositely spaced openings substantially the shape of an inverted T and a cover member for the jar having a circular body portion, a pair of oppositely spaced arms extended outwardly from said body portion 80 of the cover member, said arms being designed to be received in said inverted T-shaped openings and to have a portion projected beyond the side of the jar for permitting them to be engaged for rotating 85 the cover member for the purposes stated.

2. In a device of the class described, a jar having a contracted neck provided with an annular rabbet, said jar having a pair of openings arranged with cam surfaces and 90 a notch at the inner ends of said cam surfaces, a cover member having a portion adapted to be received in said rabbet, a pair of arms formed on the cover and adapted to be received in said openings, said arms being designed to extend into said notches for holding the cover in locked position, the arms being extended beyond the outline of the jar, whereby they may be engaged for manipulating the cover member for the 100 purposes stated.

3. In a device of the class described, a jar having a contracted neck provided with an annular rabbet, said jar having a pair of 105 openings arranged with cam surfaces and a notch at the inner ends of said cam surfaces, a cover member having a portion adapted to be received in said rabbet, a pair of arms formed on the cover and adapted to be received in said openings, the parts 110 being so arranged that when the arms of the cover member are in the openings, the rotation of the cover member will cause the arms to engage the cam surfaces for causing the cover member to be pressed 115 downwardly and then permit them to be received in the notches at their inner ends of the cam surfaces for securely holding the cover in its down-pressed position for the purposes stated.

HARRY RUBINSON.
